UNITED STATES PATENT OFFICE.

CARL ELIS ELLISON, OF NORRKOPING, SWEDEN, ASSIGNEE TO AKTIEBOLAGET MANUS,
OF NORRKOPING, SWEDEN, A COMPANY OF SWEDEN.

PULSATOR FOR SUCTION MILKING MACHINES.

Application filed September 9, 1926, Serial No. 132,357, and in Sweden September 18, 1925.

The present invention relates to an improvement in such pulsators for suction milking machines which are provided with an oscillating rotary slide actuated by one or more reciprocating pistons or the like and in which are provided passages which in the different positions of the slide put those chambers which surround the teat spaces proper in the teat cups of the machine, and in which a discontinuous suction is to be produced, alternately in communication with the outside air and with a suction conduit, said rotary slide being made as a plane slide in such manner that its passages open in a plane surface of the slide. The invention consists principally in that the oscillating rotary slide bears with said plane surface against a plane surface on a stationary part of the pulsator in which surface the passages leading to the teat cup chambers and to the suction conduit open, and that the said stationary part is formed as a ring through which extends a pin provided on the slide by means of which pin the required rotational movement is transmitted to the slide from the reciprocating piston or pistons. By this arrangement the advantage is attained that the slide becomes protected as far as possible against the influence of obliquely directed forces, so that it will be uniformly worn and that during the use of the machine the slide will work itself tighter and tighter against its seat. In this manner the packing becomes better and better, and the milking machine will work reliably and to full efficiency also after a long use. This advantage is of particular importance in respect of milking machines since such machines are as a rule used on farms where the facilities for making repairs are very small and the procuring of repair parts entails a considerable delay.

In the accompanying drawing a suitable embodiment of the invention is illustrated by way of example. Fig. 1 shows a pulsator according to the invention viewed from the side and partly in section on the line I—I in Fig. 2. Fig. 2 shows the same pulsator viewed from above and partly in section on the line II—II in Fig. 1, and Fig. 3 also shows a section through the slide on the line II—II in Fig. 1, but with the slide in the opposite position to that shown in Fig. 2.

In the embodiment illustrated, a portion 55 of the casing of the pulsator is formed in the

usual manner as a cylinder 1 in which two pistons 2 secured to a common piston rod 3, are reciprocable. Two conduits 4 and 5 extend along the upper side of the cylinder and lead to the two ends of the cylinder 1, choke screws 6 and 7, respectively, being inserted in said conduits by the aid of which screws the speed of movement of the pistons may be controlled. To the piston rod 3 two abutments 8 and 9 are secured at a distance from one another. The outer end of an arm 10 projects in between said abutments, said arm being secured to a pin 12 rotatably journalled in a stationary portion 11 of the pulsator casing, and being actuated by a coil spring 13 which is arranged in the usual way in such manner that it tends to turn the arm 10 to one or the other of its extreme positions as soon as, owing to the movement of the pistons, said arm has been moved past its middle position perpendicular to the piston rod 3. The pin 12 is provided at its upper end with two projecting arms 14 which play in cut-outs 15 in a rotatable sleeve 16 provided with a central pin 17 projecting upwards into a ring 18 which is rigidly mounted in the pulsator casing. With said ring cooperates the rotatable plane slide 19 which is provided with a central square pin 20 which projects downwards into a bearing sleeve 21 mounted in the ring 18, and engages a corresponding cut-out in the pin 17 in such manner that the slide 19 will always be entrained upon rotation of the sleeve 16 in one direction or the other. The rotational movement of the sleeve 16 and thus also of the slide 19 is limited by two stops on the member 11, not illustrated in the drawing. A cap 22 is provided above the slide 19 and is retained in position by means of a spring 23 capable of being turned, said cap being provided with a number of apertures 24 through which the outside air has free access to the upper side of the slide 19.

In the rotary plane slide 19 there are provided two passages 25 and 26 crossing each other and the ends of which are directed downwards so that they open in the plane lower face of the slide, which face bears against the plane upper face of the stationary ring 18, and also two passages 27 and 28 which extend straight through the slide from its upper side to its lower face. The two first mentioned passages 25 and 26 are adapted to cooperate with an angular passage 29 in the stationary ring 18 which passage is in 110

communication, through a passage 30 in the pulsator casing, with a nipple 31 adapted to be connected through a hose or the like with the conduit to the vacuum pump driving the machine, and also with two other angular passages 32 and 33 in the stationary ring 18. Said two last-mentioned passages are in communication with the conduits 4 and 5, respectively, leading to the ends of the cylinder 1, and also with two nipples 34 and 35, respectively, which are put in communication through hose or the like with those suction and pressure chambers in the teat cups of the machine in which a discontinuous suction is to be produced. Finally, the two air passages 27 and 28 in the rotary plane slide also cooperate with the passages 32 and 33 in the ring 18.

In the positions of the various parts illustrated in Fig. 2 the suction through the passages 30, 29, 26, and 33 acts through the conduit 5 in the upper end of the cylinder 1 and also through the nipple 35 in the above-mentioned suction and pressure chambers in two of the four teat cups of the machine. Simultaneously, the suction and pressure chambers in the two other teat cups, as well as the lower end of the cylinder 1, are in communication with the outside air through the passages 32 and 27 and the apertures 24 in the cap 22. Owing to the suction in the upper end of the cylinder 1 the pistons 2 begin to move upwards in Fig. 2, the arm 10 being entrained by the abutment 8 on the piston rod 3. When the arm 10 has been turned in this manner so far upwards that it has passed the above-mentioned middle position, it will be rapidly turned by the spring 13 to its opposite extreme position, that is to say, it will come to bear against the abutment 9. During this last mentioned rotation the sleeve 16 is entrained by the arms 14, and thus also the slide 19, so that said slide is moved over to the position illustrated in Fig. 3. In this position of the slide the suction through the passages 30, 29, 25, and 32 acts through the conduit 4 in the lower end of the cylinder 1, and also through the nipple 34 in those suction and pressure chambers in the teat cups which were previously in communication with the outside air, whereas those suction and pressure chambers in the teat cups in which there was previously suction, as well as the upper end of the cylinder 1, are now in communication with the outside air through the passages 33 and 28. As a result the pistons 2 again begin to move downwards so that the slide 19 is moved back to the position shown in Fig. 2, and so forth. Since during these rotational movements the slide 19 always bears with its plane lower face against

the plane upper face of the stationary ring 18, against which it is maintained bearing by the air pressure acting on its upper side, and moreover, since said slide is well guided by the pin 20 in the bearing sleeve 21, through which pin the rotational movements are transmitted to the slide, so that the slide is protected from being influenced by obliquely directed forces, said slide will wear itself into place during the use of the machine, so that the bearing between the slide and the ring 18 will gradually become tighter and tighter. In this manner the machine will work reliably and to full efficiency also when the slide has become worn after the machine has been used for some time.

The embodiment above described and illustrated in the drawing is only to be regarded as an example, and it will be understood that it may be modified in several ways in respect of its details without departing from the principle of the invention.

I claim:

1. In a pulsator for suction milking machines the combination of a casing, a plane slide oscillatable in said casing, said slide having passages opening in a plane surface on said slide, said casing having a plane annular seating surface against which said plane surface on said slide bears, passages in said casing opening in said plane seating surface and adapted to register with said passages in said slide, a pin on said slide passing through a central aperture in said annular seating surface, at least one piston reciprocable in said casing, and means transmitting motion from said piston to said pin.

2. In a pulsator for suction milking machines the combination of a casing, a plane slide oscillatable in said casing, said slide having passages opening in a plane surface on said slide, said casing having a plane annular seating surface against which said plane surface on said slide bears, passages in said casing opening in said plane seating surface and adapted to register with said passages in said slide, a pin on said slide passing through said annular seating surface, said pin having an edged end, a second pin rotatably journaled in said casing in alignment with said first-mentioned pin and provided with a cut-out of a shape corresponding to the edged end of said first-mentioned pin, said edged end of said first-mentioned pin engaging said cut-out in said second pin, at least one piston reciprocable in said casing, and means transmitting and transforming the reciprocating movement of said piston into oscillatory movement of said second pin.

CARL ELIAS ELLISON.
